Primary Examiner — Garth Rademaker*Assistant Examiner* — Katelin G Kloberg(74) *Attorney, Agent, or Firm* — DuBois, Bryant & Campbell, LLP; William D. Wiese(57) **CLAIM**

The design for a lid for drinking container, as shown and described.

DESCRIPTION

FIG. 1 is a front perspective view of a lid for drinking container, showing our new design within an environment of use;

FIG. 2 is a top view of a lid for drinking container;

FIG. 3 is a bottom view thereof;

FIG. 4 is a left side view thereof; and,

FIG. 5 is a right side view of thereof.

The broken lines shown in FIG. 1 depict environmental subject matter that forms no part of the claimed design. The broken lines shown in FIG. 3 depict portions of the article that form no part of the claimed design.

1 Claim, 5 Drawing Sheets(56)
